NATHAN KASDAN, OF NEW YORK, AND DANIEL POLLACK, OF BROOKLYN, NEW YORK,
ASSIGNORS TO MAJESTIC METAL SPECIALTIES, INC., OF NEW YORK, N. Y., A COR-
PORATION OF NEW YORK.

VANITY CASE.

Application filed February 4, 1926. Serial No. 85,836.

This invention relates to improvements in vanity cases more particularly of the type which is adapted to contain loose face powder. One of the objects of the invention is to provide suitable means for containing the powder so that the powder will be automatically fed when a powder puff is properly applied to the containing means. Another object of the invention is to provide means for holding a quantity of powder in a compact, neat and convenient form for application to a powder puff. Another object of the invention is to provide powder containing means with an aperture into which powder will automatically feed when a valve is opened by pressure of a powder puff, the valve forming a part of a tray which supports the powder. Other general objects of the invention are to provide attractive, convenient and simple vanity cases for containing a powder and with which may be associated a lid containing a mirror.

These being among the objects of the present invention, the same consists of certain features of construction and combinations of parts to be hereinafter described and then claimed with reference to the accompanying drawings illustrating the preferred embodiments of the invention, in which

Fig. 1 is a plan showing the vanity case as composed of two casing sections, the sections being swung to open position;

Fig. 2 is a section on the line 2—2 Fig. 1;

Fig. 3 is an enlarged section of the box member and its contents, a portion of the lid member hinged thereto being shown;

Fig. 4 is a section on the line 4—4 Fig. 3, on the same scale as Fig. 2;

Fig. 5 is a perspective view of a spring for holding the valve of the powder tray closed;

Fig. 6 is an enlarged section on the line 6—6 Fig. 1, one of the securing catches being shown slightly out of place for a convenient illustration of the construction; and

Fig. 7 is a section corresponding to Fig. 3 as to dimensions but illustrating a modified form of the invention.

The improved vanity case may conveniently be provided with two casing sections 10, 11, respectively constituting a box mem-

ber and a lid, the same being connected by means of a hinge 12. Preferably but not necessarily, these casing sections are of circular form and they are so constructed that one section may be fitted to the other so as to close the vanity case. These parts are shown in Figs. 1 and 2 in assembled relation and they also show that the lid 11 may have fitted thereto a frame 13 which supports a mirror 14 in the top of the lid.

A frame of appropriate construction and shape is fitted into the box member 10, and it preferably comprises an outer wall 15, an inner wall 17 separated therefrom, and a connecting wall or web 16. The outer and inner walls 15 and 17 are concentric with each other when the frame is of the form of an annulus, while the connecting wall 16 is at the top of the box member 10. Preferably, the top wall 16 slopes downwardly from the outer wall 15 of the frame. Suitable means are provided for securing the frame 15, 16, 17 into the box member 10, which in part comprises a lug 18 extending inwardly of the box member 10 and into a hole 18^a cut in the outer wall 15 of said frame. The frame securing means may also comprise spring catches 19, 20 struck out from the outer wall 15 at appropriate points, as shown more clearly in Fig. 4, and each of these catches is adapted to engage under a shoulder 20^a when the frame has been engaged with the lug 18 and snapped into the box member.

A cover plate 21 is provided, the outer edge 22 of which is folded back on itself and is adapted to overlap the connecting wall 16 of the frame referred to, when the outer flange 23 of the cover is pressed down into frictional engagement with the inner wall 17 of the frame 15, 16, 17. It will be seen that, when the cover 21 is pressed home, the flange 23 on the inner surface of the overlapping edge 22 thereof will snugly hug or lie against the adjacent surfaces of the frame 15, 16, 17. Cover plate 21 is shaped somewhat like a flattened funnel, that is to say, it tapers towards its center, or, more specifically, flares outwardly from a flange 24 formed on it and which surrounds an aperture 25 through the cover plate. Prefer-

ably, there is a single aperture 25 and it is of comparatively large size, amply sufficient to permit a powder puff to be pressed therewith. It may be stated that the space afforded in the vanity case between the mirror 14 and the cover plate 21 provides for receiving the powder puff and holding it in the vanity case when the same is closed.

Cover plate 21, in association with a tray 26, provides a chamber adapted to receive loose face powder 27. The tray 26 has a peripheral flange 26^a which has a bearing on the outer surface of the frame wall 17, so that the tray is rendered movable up and down away from the cover plate. A spring 28 is clearly shown in Fig. 2, where it will be seen that a portion of the tray corresponding substantially in size with the area of the opening 25 in the cover plate, acts as a valve to close the said opening. However, when the user presses a powder puff through the aperture 25 and onto the tray 26, the spring pressure is overcome and powder is allowed to feed onto the valve portion of the tray and into the aperture, as shown in Fig. 3, so that the puff may take up the desired quantity of powder. When the pressure of the puff is removed, the spring automatically returns the powder tray to close the aperture 25.

As shown in Figs. 1 and 6, the frame 15, 16, 17 is provided in its connecting wall 16 with a depression 29 which permits the user to introduce a finger nail beneath the overlapping edge 22 of the cover plate, so that the same may be conveniently lifted and the tray 26 exposed for refilling it with powder. The casing sections of the vanity case, comprising the box member and the lid, may be secured together by a snap fastening, such as a catch 31 mounted on a spring 32 riveted to the box member and provided with a thumbpiece 33, whereby the catch 31 may be released from a corresponding aperture or portion of the lid 11. In order to accommodate the said fastening within the box member 10 so as to allow of depressing the spring 32, one side of the frame wall 15 is flattened at 30.

The modification illustrated in Fig. 7 will now be described. In this adaptation of the invention, the box member 35 has fitted therewith a frame 36, 37, which comprises a flange 36 snugly seated in the box member 35 and a wall 37 substantially at right angles thereto. Preferably the frame 36, 37 is formed in one piece with a tray 38, the said parts being composed of spring metal deformed into bowed or dished shape. Seated removably within the upper part of the spring metal tray 38 is a frame 40 which is provided with a funnel-like central portion 42, the opening of which is adapted to be automatically closed by the springy tray 38. However, when it is desired to allow

powder to feed from the tray, the same is depressed by a powder puff and its inherent spring action is overcome by the pressure. Preferably, the frame of the cover plate 42 has a hinge connection 41 with the frame of the tray 38, so that the said cover plate may be pushed open and a fresh supply of powder placed in the tray when necessary.

It will be obvious to skilled mechanics that various modifications may be resorted to other than the details as herein described, without departing from the spirit and scope of the invention as expressed in the appended claims.

What we claim as new is:

1. In a vanity case, means for confining powder, comprising a movable downwardly dished spring wall and an opposing fixed wall having an aperture normally closed by said spring wall, said aperture being of ample size to permit pressure of a powder puff through it onto the spring wall whereby to admit powder into the aperture.

2. In a vanity case, the combination of a box-member, a frame having a downward flange fitted into the box-member, the frame supporting an apertured cover, a powder tray confined beneath the cover, and means for causing the tray to act as a valve to automatically close the aperture.

3. In a vanity case, the combination of a box-member, a frame fitted into the box-member and supporting a separate apertured cover, a downwardly dished powder tray confined beneath the cover, means for causing the tray to act as a valve to automatically close the aperture, and a hinge connection between the frame and tray.

4. In a vanity case, the combination of a box-member, a frame fitted into the box-member, means secured to the frame to confine powder, and comprising a removable apertured cover having a substantially horizontal edge overlapping the frame, and means to permit the finger nail to be engaged under the overlapping edge, whereby to raise the cover.

5. In a vanity case, the combination of a box-member, a frame fitted therewith, a powder tray fitted movably to said frame, a cover fitted to the frame and having an aperture, and a plate spring having its opposite ends bearing on the box-member and its intermediate portion bearing on the tray for causing the tray to close the aperture.

6. In a vanity case, the combination of a box-member, a frame having outer and inner side walls and a connecting wall, the outer wall fitted to the box-member, and both walls extending inwardly from the connecting wall and into the box-member, a powder tray provided with a flange having a loose bearing around the inner side wall, and a cover having a flange fitted to the inner sur-

face of the inner side wall, said cover having an aperture, and a spring acting on said tray to close the aperture and to urge the tray-flange forwardly on the said inner side wall.

7. In a vanity case, the combination of a box-member, a frame having outer and inner side walls and a connecting wall, the outer wall fitted to the box-member, and both walls extending inwardly from the connecting wall and into the box-member, a powder tray provided with a flange having a loose bearing around the inner side wall and a cover having a flange fitted to the inner surface of the inner side wall, said cover having an aperture, and a spring acting on said tray to close the aperture, the cover hav-

ing a substantially horizontal edge overlapping the connecting wall of said frame.

8. A vanity case, comprising the casing proper, a tray therein for containing a substantial quantity of powder, a cover for the tray provided with an aperture, and a frame associated with the edge of the tray and fixed in the case, and the apertured cover fitted into said frame, said tray being provided with means for causing it to act as a valve to close the aperture, and the tray being compressible when pressure thereon is exerted through said aperture, thereby to feed powder into the aperture.
